CLAIM

The ornamental design for a container lid, as shown and described.

DESCRIPTION

FIG. 1 is a front perspective view of a container lid showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view of an alternative claimed configuration of a container lid showing our new design.

The broken lines depicting the remainder of the container lid form no part of the claimed design. The dash-dot-dash lines in FIG. 8 represent boundaries of the claimed design and form no part thereof.
